Primary Examiner — Nicole C Shiflet*Assistant Examiner* — Karen M. Jones(74) *Attorney, Agent, or Firm* — Merchant & Gould P.C.(57) **CLAIM**

The ornamental design for an aerosol generator as shown and described.

DESCRIPTION

FIG. 1 is a top front perspective view of an aerosol generator showing the claimed design;
FIG. 2 is a bottom rear perspective view thereof;
FIG. 3 is a bottom front perspective view thereof;
FIG. 4 is a front view thereof;
FIG. 5 is a rear view thereof;
FIG. 6 is a top view thereof;
FIG. 7 is a bottom view thereof;
FIG. 8 is a left view thereof;
FIG. 9 is a right view thereof; and,
FIG. 10 is a partial detail view of FIG. 2.

The broken lines in the drawings illustrate portions of the aerosol generator that form no part of the claimed design. The dot-dash broken lines in FIG. 10 illustrate the boundaries of the partial detail view of the aerosol generator that form no part of the claimed design.

1 Claim, 10 Drawing Sheets(56)
